BARBER'S CHAIR HEADREST

Mae Spahr Grey, San Francisco, Calif.

Application June 4, 1946, Serial No. 674,296

6 Claims. (Cl. 155—176)

1

This invention relates to head rests for reclining chairs such as barber chairs or the like.

It is customary to provide the usual reclining barber chair with a removable head rest. The head rest is inserted in a holder on the upper back of the chair when a customer is to be shaved, and serves to support the customer's head when the chair and occupant are in reclining position. As a sanitary measure, the head rest is provided with a paper covering upon which the customer's head rests, the paper emanating from a roll, and intended to be drawn out and torn off after each use to provide a fresh covering for each customer's use.

Barbers have found that in the rush attending an unusual influx of customers, the advancing of the paper strip after each customer is sometimes forgotten. This is contrary to health regulations in many communities, and may lead to the spread of skin infections, or other infections or commercial diseases.

Other defects noted in present devices of this character are the lack of angular adjustability of the head rest, the frequent breaking of the supporting posts due to repeated insertion and removal of the head rest, and the difficulty encountered in putting a new roll of paper in the head rest.

The general object of the present invention is to provide a head rest which will overcome these deficiencies.

A more specific object of the invention is to provide a device of this character which will automatically advance the paper strip after a customer has rested his head upon the device and the chair is then returned to its upright position.

Another object is to provide such automatic feed, the operation of which may not be initiated while the chair remains in an upright position.

It is further contemplated to provide a head rest in which the insertion of a fresh roll of paper is facilitated, and the need for a roll-supporting rod or spindle is dispensed with.

It is also contemplated to provide such a device which is adjustable, whereby the angular relationship of the head rest with respect to the chair may be varied.

A still further object of the invention is the provision of a head rest which is more readily attachable to, and detachable from, the chair back.

Other objects of the invention will be apparent from the following description taken in conjunction with the drawings which accompany and form a part of this specification.

2

In the drawings:

Figure 1 is a vertical transverse section through a barber chair head rest incorporating the principles of the present invention, the view being taken substantially on the line 1—1 of Figure 2;

Figure 2 is a longitudinal vertical section taken on the line 2—2 of Figure 1;

Figure 3 is a horizontal section taken on the line 3—3 of Figure 2;

Figure 4 is a fragmentary section taken on the line 4—4 of Figure 2, showing the paper-feeding gear mechanism;

Figure 5 is a fragmentary sectional view taken on the line 5—5 of Figure 2;

Figure 6 is a view similar to Figure 1, but with the head rest tilted as when the chair is in reclining position;

Figure 7 is a sectional view taken on substantially the same line as Figure 4, with the head rest in tilted position, and the mechanism in the positions assumed when a customer's head has rested upon the cushion surface;

Figure 8 is a view of the trigger mechanism when in closed position;

Figure 9 is a view of the trigger mechanism and paper-feeding gearing showing the movement of the parts when the head rest is tilted upwardly to release position;

Figure 10 is a fragmentary section taken on the line 10—10 of Figure 6;

Figure 11 is a fragmentary view of one end of the paper-feeding roller and its associated ratchet mechanism;

Figure 12 is a section taken on the line 12—12 of Figure 11;

Figure 13 is a section taken on line 13—13 of Figure 2 illustrating the angle adjusting mechanism; and

Figure 14 is a section on the line 14—14 of Figure 1.

Referring to the drawings in detail, the invention comprises a head rest 1 of generally conventional shape and appearance, and having the usual toothed supporting posts 2 for adjustable insertion into the conventional holder (not shown) affixed to the back of a barber chair. As is usual, a padded cushion 3 covers the upper surface of the head rest, and a strip of paper 4 extending from a roll 5 covers the cushion and passes between feed rollers 6 and a pressure roller 7.

Automatic means are provided to rotate feed rollers 6 when the chair carrying the head rest assumes an upright position after having been

in reclining position and the weight of a person's head has been upon the head rest.

To accomplish this, in the embodiment shown, the head rest is formed as a two-part housing, the sections of the housing being constructed upon two castings, one casting forming a back plate 8 attached to the upper end of the supporting posts 2, and the other casting 9 comprising a central plate 10, and the end walls 11 and 12 of the head rest. The end walls are bridged by the head cushion 3 and all parts of the head rest housing structure, with the exception of the back wall 8, are supported upon the end walls. The two castings are pivotally connected at their lower ends by means of a pivot rod 13, extending the width of the head rest, and held in position by cap screws 14 at either end. Back plate 8 is of such width that it fits between the end walls 11 and 12. The two castings are normally urged apart by coiled springs 15 interposed between the plates 8 and 10 at a distance from the pivot near the upper edges of the plates, and held in position by seating upon bosses projecting from the two plates. This construction permits the casting 9 and its associated parts of the housing to be yieldingly rocked about the pivot 13 when the weight of the customer's head rests upon the cushion 3, thus causing plate 10 to approach the back plate 8.

The rocking of casting 9 is limited in both its inward and outward movement by studs 16 which project inwardly from the end walls 11 and 12, and engage the ends of T-slots 17 in the lugs 18, formed at the end of back plate 8 and projecting interiorly of the head rest. The slots are of T-formation to facilitate assembly.

The rocking movement of the casting 9 serves through appropriate gearing, to be described, to rotate the paper feed rollers 6 to advance the paper strip.

Pivotally attached, as at 19, to the back plate 8 at one upper corner thereof, is a rack bar 20 which extends inwardly to mesh with a gear 21 carried by the end wall 12. As casting 9 rocks carrying gear 21 with it, the gear is rotated by traveling along the rack 20. Fixed to gear 21 to rotate with it is a segmental gear 22 meshing with a wide gear 23, which gear 23 also engages gear 24 of a unitary gear and ratchet, the ratchet being indicated by 25.

The unitary gear and ratchet is loosely mounted upon shaft 26 which is journaled in the end walls and carries the paper feed-rollers 6. The feed-roller may be a continuous one extending the length of the head rest, but it is shown as a plurality of spaced rollers fixed to the shaft to rotate therewith. To one of the rollers, the one on the left as viewed in Figure 2, a pawl 27 is pivoted, the pawl cooperating with the ratchet 25 to rotate the roller 6 in one direction, but permitting the ratchet to run freely in the opposite direction without imparting rotation to rollers 6. Pawl 27 is constantly urged toward ratchet 25 by a leaf spring 28. The gearing and ratchet and pawl mechanisms are so arranged that the overrunning action of the ratchet will take place as the casting 9 is rocked toward the back plate 8, and as the reverse movement takes place under the influence of springs 15 the paper feed-rollers will operate to advance the paper.

The arrangement of the gearing is such that gears 21 and 23 are on opposite sides of the shaft 26. As is clearly shown in Figure 7, this arrangement permits the use of shaft 26 as a bearing surface for the back of rack bar 20 to

hold the rack bar in continuous mesh with the gear 21. Segmental gear 22 is mounted with gear 21 but meshes with gear 23 on the opposite side of shaft 26 necessitating the provision of a slot 29 to receive shaft 26. Slot 29 not only permits oscillation of segmental gear 22, but, by limiting the movement of the gear also serves to prevent accidental unmeshing of the segmental gear 22 or rack bar 20 during assembly or disassembly of the head rest.

The above-described mechanism will feed the paper strip whenever pressure is exerted upon the cushion 3 and then removed. However, automatic latch mechanism is provided to prevent the rocking of casting 9 when the head rest is in a vertical position, but to permit it when the head rest is in reclining position, and trigger mechanism serving to hold the casting 9 in operative position after having been rocked and released only when the head rest is again brought to vertical position.

The trigger mechanism comprises a trigger member in the form of a bell-crank lever 30 pivoted at 31, to a lug 32 projecting from the back plate 8; one arm of the lever being provided along one edge with teeth 33 to be engaged by a dog 34 pivotally mounted upon a bracket 35 fixed to the central plate 10 of casting 9. Dog 34 has its end turned at right angles to its body portion, the offset end passing through an arcuate slot 36 in the bracket 35. A spring 37 normally urges the dog 34 downwardly toward tooth-engaging position, the downward movement of the dog being limited by striking the end of slot 36.

Trigger lever 30 is movable about its pivot 31 to bring it to and away from dog-engaging position. In other words, the lever may be rocked so that its toothed surface will engage and lift the dog 34, or it may be rocked out of engagement with the dog so that the dog comes to rest against the end of slot 36 and the dog and lever are entirely separated. When the lever is in dog-engaging position and pressure is applied upon the cushion 3, casting 9 will rock about its pivot and dog 34 will ride over the ratchet teeth 33 of the lever, coming to rest in engagement with one of the teeth when casting 9 reaches the limit of its inward movement, holding the casting in rocked position.

Trigger 30 is tripped to release casting 9 by means of a gravity-operated, pivoted weight 38. Weight 38 is fixed to pivot pin 39 which is journaled in lugs 40 extending from back plate 8. Pivot pin 39 also has fixedly secured to it a cam 41 which underlies a flange 42 turned over from the actuating arm of the lever 30. Secured to weight 38 and overlying flange 42 is a trip rod 43. From the showing in Figures 1, 5, 6, 8, and 9, the operation of the trip will readily be seen. When the head rest is tilted to reclining position, the center of gravity of weight 38 passes over the pivot point 39 and weight 38 swings to the right, as seen in these figures, and cam 41 will rotate, striking flange 42 of lever 30 and causing the lever teeth to engage dog 34. When the head rest is raised the weight pivots back to the left, causing the cam to move from engagement with flange 42, and trip rod 43 carried by the weight will strike the opposite face of the flange, rocking the lever 30 and disengaging the teeth from the dog.

To prevent the rocking of casting 9 to set the trigger mechanism when the head rest is in upright position, a latch lever 44 is loosely mounted on pivot 39 and attached to weight 38 by

means of a pin and slot connection 45. Lever 44 engages a notched stud 46 projecting from plate 10 when the head rest is upright, preventing the casting 9 from being rocked on its pivot as shown in Figures 1 and 5. As the head rest is tilted to the position shown in Figure 6, the weight 38 swings on its pivot and carries latch lever 44 with it, freeing the casting 9 so that it may move. The pin and slot connection between the latch lever and weight provides lost motion between the two so that the weight will deliver an impact blow to the latch lever to ensure its release from the notch in stud 46 in the event a customer's head is resting against cushion 3 when the chair is tilted, and to permit the latch lever to have a greater range of travel than the weight.

To facilitate the insertion of a fresh roll of paper, a paper container 47 extends substantially the full length of the lower portion of the head rest. The paper container is arcuate in cross-section, providing an opening 47' extending the full length of the container. The container is pivoted to the pivot pin 13 and urged toward closed position with the opening 47' inside the head rest housing by means of a spring 48 which encircles pivot pin 13 and has one end bearing against back plate 8 and the other end against the paper container. The inward movement of the container is limited by striking flanges 49 projecting inwardly from the side edges of the back plate 8. A metal sheet 50 extends from center plate 10 of casting 9, and has its outer end curved downwardly in overlapping relation to the edge of paper container 47. The position of rest of the paper container is such that the overlapping edges of the paper container and curved end of sheet 50 are spaced apart sufficiently to permit the free passage of the paper strip therebetween.

Back plate 8 is provided with a pair of spaced ears 51, between which is pivoted one member 52 of a coupling 53, the coupling being for the purpose of removably connecting the head rest proper to the supporting posts 2. Coupling member 52 is provided with a recess 54 to receive tongue 55 extending from a bridge-piece 56 which is secured to the upper ends of supporting posts 2 and holds the supporting posts in proper spaced relation.

Tongue 55 is provided with a slot 57 extending from the upper edge of the tongue downwardly. One side face of the tongue is countersunk as at 58, the bore being concentric with the bottom of the slot and of a diameter greater than the width of slot 57, and to a depth of approximately half the thickness of the tongue. Slot 57 is adapted to slidably embrace a locking pin 59 carried by the coupling member 52 and disposed across the recess 54. One end of pin 59 is enlarged, as at 60, to seat in the countersunk bore 58 to lock the tongue within the recess when the pin is moved to the right, as shown in Figure 1. Coupling member 52 has an enlarged bore 61 to receive an enlarged head 62 on the opposite end of pin 59. A spring 63 encircles the pin within the bore and abuts the bottom of bore 61 and the underside of head 62 to urge the pin to tongue-locking position. The head 62 projects beyond the outer face of coupling member 52 to serve as a thumb button to depress the pin to move the enlarged portion 60 from the bore 58 and permit the coupling member and tongue to be engaged or disengaged. By reason of this construction, the

head rest may be removed from the chair by separation from the posts at the coupling 53. The supporting posts thereby become a means for vertical adjustment for the head rest in the usual manner but remain in the usual head rest holder and need not be removed therefrom.

Coupling member 52 carries a quadrant 64 which extends through slot 65 in back plate 8 to the interior of the head rest. The quadrant 64 is provided with a plurality of holes 66, the holes being arranged in an arc having the pivotal connection 67 between the coupling member 52 and ears 51 as its center. Holes 66 are arranged to be selectively engaged by a locking rod 68 slidably mounted on the interior of the head rest in bearings 69 carried by the back plate 8. Rod 68 is provided with an enlargement 70 midway between its ends, and a coiled spring 71 is placed around the rod to bear against the enlargement 70 and one of the bearings 69 to normally urge the rod into engagement with one of the holes 66 in the quadrant 64. A bell crank lever 72 is pivoted to a lug 73 projecting from the back plate 8 and has the outer end of one arm in engagement with the enlargement 70 on the rod 68 on the opposite side from spring 71. The other arm of the bell crank is pivotally connected to an operating finger piece 74. Finger piece 74 passes through an opening 75 in back plate 8 to the outside of the head rest. Pressure upon the finger piece rocks the bell crank, moving the locking pin against the pressure of spring 71 to disengage the hole in the quadrant.

In operation, the supporting posts 2 are attached to the usual holder on the back of a barber chair, and the head rest proper is attached to the posts by means of the coupling 53. The head rest is then adjusted to the desired angle by depressing the finger piece 74 to withdraw the pin 68 from the hole 66 with which it is engaged, and the head rest is rocked about the pivot 61 to the desired angle, whereupon the finger piece is released and the locking rod 68 moves into the hole 66 with which it is in alignment. The paper container 47 is rocked about the pivot rod 13 to the position shown in dotted lines in Figure 1, with the opening 47' exterior of the housing, and a roll of paper is dropped into the container and the container released, whereupon the spring 48 will return it to its normal position. The end of the paper strip is then brought across the face of the cushion 3 and inserted in the slot at the top of the head rest and between the paper feed rollers 6 and the pressure roller 7. By rotating nob 76, fixed to the end of paper feed roller shaft 26, the paper can be advanced any desired amount. The paper pressure roller 7 has its trunnions fitted into slots in the end walls 11 and 12 and the casing is provided with a pair of leaf springs 77 to engage the trunnions and hold them in the slot. The force which the pressure roll exerts upon the paper may be adjusted by tightening or loosening screws 78 of the housing to regulate the pressure of springs 77 upon the trunnions.

With the chair in upright position, the head rest will appear as in Figure 1. The weight 38 is swung forwardly of the pivot and the latch lever 44 is in engagement with the notched stud 46, locking the paper-advancing mechanism in inoperative position.

When a customer is to be shaved, the chair is tilted backward to reclining position and the head rest assumes the angular position shown in Figure 6. As the center of gravity of the weight

38 passes to the opposite side of its pivot 39, the weight swings in a clockwise direction as shown in Figure 6, and the pin 45, striking the end of the slot in latch lever 44, causes lever 44 to move from engagement with the notched stud 46 to release the paper actuating mechanism for operation. When the customer's head rests upon the cushion 3, casting 9 is caused to rotate about pivot rod 13, moving plate 10 toward back plate 8. The swinging of weight 38 causes cam 41 to rotate, rocking trigger lever 30, to bring teeth 33 into operative engagement with dog 34. As plate 10 approaches plate 8, dog 34 rides over teeth 33, coming to rest in one of the teeth when the movement of plate 10 ceases. This position of the trigger mechanism is shown in Figure 8. During the pivotal movement of casting 9, gear 21 is caused to rotate by moving along rack bar 20, and the rotation of gear 21 is transmitted to segmental gear 22 and gears 23 and 24. Due to the overrunning action of the ratchet and pawl mechanism 25-27, no motion is imparted to the paper feed roller shaft or rollers. This position of the paper feeding gear train is shown in Figure 7.

As long as the head rest remains in reclining position, the parts will remain in the position shown in Figures 7 and 8, due to the locking engagement between teeth 33 on the trigger lever and the dog 34, even though the customer may lift his head or turn it from side to side.

When the chair is returned to upright position, the center of gravity of weight 38 passes to the opposite side of pivot 39 and the weight swings in a counterclockwise direction, causing trip rod 43 to strike flange 42 of trigger lever 30, rocking the lever to move the teeth 33 from engagement with the dog 34. This releases casting 9 from back plate 8, and the springs 15 which were compressed by the inward movement of plate 10 expand, returning plate 10 to its original position. During this outward movement, gear 21 rides back over rack 20, which imparts a reverse rotation to the gear and through gear 21 to segmental gear 22 and gears 23 and 24. When the gearing rotates in this direction, pawl 27 is in engagement with ratchet 25 and the rotational movement is imparted to the feed roller 6, causing the paper strip to advance. As the return movement is quite sudden, the paper feed rollers 6 are set into rotation with considerable force and will continue to rotate, through the overrunning of the ratchet and pawl mechanism, after the gears have ceased to rotate.

The amount of overrunning may be controlled by adjusting the pressure with which pressure roller 7 bears upon the paper sheet. The springs 11 act as friction brakes on the trunnions of the roller 7 and the greater pressure applied, the more braking action obtained.

While I have in the above described what I believe to be a preferred and practical embodiment of the invention, it is to be understood that the specific embodiment shown and described is simply by way of illustration, and the invention is to be limited only by the scope of the appended claims.

Having thus described my invention, I claim:

1. In a reclining chair headrest of that type having an automatic feed for a paper covering emanating from a roll within the housing wherein the headrest is formed of a two-part housing with the sections of the housing being pivoted together for relative movement, and in which the paper is advanced by feed rollers operable upon

relative movement between the sections of the housing, in combination with said feed rollers and said two-part housing: a gear train to rotate one of said feed rollers comprising, a rack carried by one part of said housing, said feed roller being mounted upon a shaft carried by the other part of said housing and a gear mounted on said shaft, a gear mounted on said other part of said housing at one side of said roller shaft and in mesh with said roller shaft gear, and a sector gear mounted for rotation with said rack gear and in mesh with said wide gear and having an arcuate slot to receive the said roller shaft, whereby relative movement of said housing parts will impart rotation to said roller shaft and said roller shaft may serve as a backing for said rack to hold said rack in mesh with said rack gear.

2. In a device as claimed in claim 1, the slot in said sector gear being of such length that the roller shaft will abut the end of said slot to prevent said rack from running off of said rack gear.

3. In a device as claimed in claim 1, the slot in said sector gear being of such length that the roller shaft will abut the end of said slot to prevent said rack from running off of said rack gear, and an overrunning mechanism between said roller shaft gear and said shaft.

4. A head rest for a reclining chair comprising, a two-section housing, one of said sections adapted to be attached to said chair and the other section being pivotally supported upon the first said section, a paper container, paper feed rollers, one of said rollers being mounted upon a shaft carried by one section of said housing and a gear mounted on said shaft, a rack carried by the other section of said housing, a rack gear carried by said one section of said housing at one side of the axis of said roller shaft, said rack extending between said shaft and said rack gear, a wide gear carried by said one section of said housing in mesh with said roller shaft gear, and a sector gear mounted for rotation with said rack gear and in mesh with said wide gear and having an arcuate slot to receive said roller shaft, whereby relative movement of said housing sections will impart rotation to said roller shaft and said roller shaft may serve as a backing for said rack to hold said rack in mesh with said rack gear.

5. In a reclining chair headrest of that type having a two-section housing wherein relative movement between the sections of the housing cause the automatic advancement of a paper covering emanating from a roll within the housing, in combination with latch mechanism comprising, a trigger in the form of a bell-crank pivotally carried by one section of the housing and having ratchet teeth on one side of one arm and a flange at one side of the other arm, a spring actuated dog carried by the other section of said housing for engagement with the ratchet teeth on said trigger and having a stop to limit its movement in a tooth-engaging direction, and a pivotally mounted, weighted, gravity-operated lever having a cam to engage one side of the flange on said trigger and a knob to engage the other side of said flange, whereby the trigger may be moved and held in dog-engaging and dog-disengaging positions as the headrest is tilted.

6. In a device as claimed in claim 5, a second latch pivotally carried by said weighted lever to bear against a portion of said housing to prevent the housing sections from moving toward one an-

other, said latch also having a pin and slot connection with said weighted lever to permit said lever limited free movement before moving the latch to release position.
